MECHANISM FOR SEPARATING CORE LAMINATIONS

Gareth G. Somerville and Aldo C. Blasioli, Pittsfield, Mass., and Russell D. Wheeler, Mellenville, N.Y., assignors to General Electric Company, a corporation of New York

Filed Oct. 1, 1962, Ser. No. 227,135
4 Claims. (Cl. 29—239)

This invention relates to a separating mechanism and more particularly to a separating mechanism for separating core laminations.

In making pre-formed, single turn magnetic cores it has been found desirable to separate the various laminations of the core in order to stagger the various joints of the final core. One method of making such pre-formed, single turn magnetic core is described and claimed in application Serial No. 227,193, filed concurrently herewith, in the name of Gareth G. Somerville, one of the inventors herein, for Method of Making Pre-Formed Single Turn Magnetic Cores, and assigned to the same assignee as this invention. As noted in that application, a single turn core is one in which each of the laminations has been cut such that it extends for approximately a single turn of the core. The invention herein described finds specific application in the method described in that application, although obviously, not limited to such method.

As described in the aforementioned application, after the core has been cut along a single plane it is desirable to separate the various laminations of the core and form them into staggered joints. Inasmuch as it is desirable that the method be performed with as much automatic equipment as possible, it is desirable to provide a mechanism to automatically separate the laminations from each other. Since all of the laminations are cut along a single plane, it is necessary that a mechanism be provided which will separate one or a plurality of laminations while holding the remaining laminations grouped together in the cut core. It is also desirable that the mechanism be such that it may be used to separate the laminations singly, or in groups of two or three laminations, as desired, for the particular type of core being constructed.

It is therefore an object of this invention to provide a novel mechanism for separating laminations of a single turn magnetic core.

It is a further object of this invention to provide a novel mechanism which will separate a lamination from a group of laminations while holding the remaining laminations together in the group.

A still further object of this invention is to provide a novel separating mechanism which may be used to separate one or more laminations from a group of laminations.

In carrying out this invention in one form, a separating mechanism is provided for separating laminations of a cut core. The separating mechanism is in the form of a rotating means which is provided with a separating means and a holding means. The separating means and the holding means are positioned about the rotatable means such that the separating means will separate laminations from a group of laminations, and the holding means will prevent other laminations of the group from being separated therefrom. The depth of the holding means and the separating means determine the number of laminations which may be separated from the group in any single separation.

The invention which it is desired to protect will be clearly pointed out and distinctly claimed in the claims appended hereto. However, it is believed that this invention and the manner in which its various objects and

2

advantages are obtained, as well as other objects and advantages thereof, will be better understood from the following detailed description of preferred embodiments thereof, especially when taken in connection with the accompanying drawings, in which:

FIGURE 1 is a front view of one form of separating mechanism according to this invention;

FIGURE 2 is a side view of the mechanism shown in FIG. 1;

FIGURE 3 is a perspective view of the separating mechanism shown in FIGS. 1 and 2;

FIGURE 4 is a front view of another form of separating mechanism according to this invention;

FIGURE 5 is a side view of the mechanism shown in FIG. 4;

FIGURE 6 is a perspective view of the separating mechanism shown in FIGS. 4 and 5; and

FIGURES 7, 8 and 9 are top and side views of the separating mechanism shown in FIGS. 4, 5 and 6 showing the operation of the separating mechanism.

In the drawings there is shown a separating mechanism in the form of a rotatable means having holding means and separating means. The holding means and the separating means are spaced about the separating mechanism such that for each revolution of the mechanism two separations will occur. However, it will be understood, that if desired, the mechanism could be designed to make only one separation for each revolution, or it could be designed to make more than two separations for each revolution.

Referring now particularly to FIGS. 1, 2 and 3 of the drawings, in which like numerals are used to indicate like parts throughout the various views thereof, a separating mechanism, designated as 10, is shown. The separating mechanism 10 is shown as a rotatable device made in a single piece, and having a head portion 12 and a hub portion 14. The head portion 12 is formed with a pair of holding members 16 and 18, and a pair of separating members 20 and 22. As can be seen, especially in FIG.

2, the depth of the holding members 16 and 18 is slightly less than the depth of the separating members 20 and 22. Stated in another way, the bottom of the holding members 16 and 18 will rotate in a plane which is separated from the plane of rotation of the edges of the separating members 20 and 22 by a small distance.

This difference or distance, indicated as W in FIG. 2, is slightly greater than the thickness of the laminations to be separated. For example, if the laminations are approximately 12 mils in thickness and it is desired to separate one lamination at a time, the distance W would be approximately 13 mils. However, if it is desired to separate two laminations at a time then the difference W would be approximately 25 mils for laminations that are 12 mils in thickness.

As can be seen from FIGS. 1 through 3, the holding members 16 and 18 are spaced substantially 180° apart about the head portion 12 of the separating mechanism 10. The separating members 20 and 22 are also spaced approximately 180° apart about the head portion 12 and are spaced approximately 90° from the holding members 16 and 18. With this construction and with the distance W approximately 13 mils, the separating mechanism 10 will provide two separations per revolution of the mechanism with a single lamination being separated at each operation. Obviously, if desired, the holding members and separating members could be designed to provide only a single separation per revolution of mechanism 10, or to provide more than two separations per revolution. Clearly, the number of laminations separated during each separation will depend upon the distance W, as has been previously described.

The hub member 14 is provided to secure the mecha-

nism 10 to any type of rotating device. An opening 24 is provided in head 12 and a bore 26, communicating with opening 24, is provided through the hub 14. A screw member 28 fits through the bore 26 with head 30 of screw 28 contacting a shoulder 32 formed between the bore 26 and the opening 24. In this manner, the separating mechanism 10 may be connected to a rotatable device for operation of the mechanism.

Referring now to FIGS. 4 through 6 of the drawing, another form of separating mechanism, designated 10', is shown. In this form of the invention the mechanism 10' is formed in two separate parts. One part 40 has a head portion 42 and a hub portion 44. The second part 46 is removably positioned on the head portion 42 and is provided with a pair of holding members 48 and 50. Separating members 52 and 54 are formed on part 40, in a manner similar to that for mechanism 10 shown in FIGS. 1 through 3. Considering especially FIG. 5 of the drawing, it can be seen that the plane of rotation of the bottom of holding members 48 and 50 is separated from the plane of rotation of the edges of the separating mechanism 52 and 54 by a small distance, which is indicated as W' in FIG. 5. In the same manner as earlier described with reference to FIGS. 1 through 3, the distance W' will be slightly greater than the thickness of a single lamination where the separating mechanism 10' is used to separate a single lamination, and of course, where more than one lamination is to be separated the distance W' will be slightly greater than the combined thickness of the number of laminations which it is desired to be separated at a single time.

Of course the holding members 48 and 50 which are formed on the member 46 are substantially 180° apart from each other and are mounted on the head member 42 so as to be separated by approximately 90° from the separating members 52 and 54. As will be understood the separating members 52 and 54 are also formed on the head member 42 so as to be substantially 180° apart about the head member 42. Thus it is seen that the construction of the separating members 52 and 54 and the holding members 48, 50, are substantially the same as that for FIGS. 1 through 3. However, by making the member 46 removable from the head member 42 it is possible to change member 46, as desired, to provide different holding members in the separating mechanism 10'. By merely providing different holding members it is possible to change the distance W' and thereby to change the number of laminations which will be separated for any given separation, rather than necessitating the change of the entire separating mechanism as would be necessary with reference to the mechanism disclosed in FIGS. 1 through 3.

Of course, it will be understood, that the distance between the holding members and the separating members will not always be 90°, as shown. In operation of the separating mechanism of this invention, it is desirable that the separating member be inserted into the laminations just before the holding member is rotated past the laminations. If the separating member is inserted into the laminations too soon, the lamination or laminations being separated may be bent and distorted, thus preventing the formation of a proper joint between the lamination ends. Clearly, the circumference of the separating device and the width of the laminations will determine the exact angular relation between the holding members and the separating members. In the form of invention shown in FIGS. 4-6, it is possible to adjust the member 46, to change the angular relation between the separating members 52, 54 and the holding members 48, 50. Thus, for changes in width of the core laminations adjustment may be made of member 46, to provide the desired angular relation to prevent distortion of the separated laminations.

In order to mount the holding members 48, 50 and the part 46 onto the part 40, the part 46 is provided with an opening 56 which extends a major portion through the

member 46. A smaller opening 58 is provided in the base of member 46 and a shoulder 60 is formed between the opening 56 and the opening 58. A bore member 62 is provided through the head 42 and the hub 44 of the part 40. A screw member 64 is provided which fits through the openings 56, 58 and bore 62 for securing members 46 and 40 together to a rotating device. The head 66 of the screw 64 contacts or butts against the shoulder 60 firmly securing the member 46 to the member 40, and also firmly securing the entire separating mechanism 10' to any type of rotating device.

In operation of either of the separating mechanisms 10 or 10', as will be understood, the holding member will ride over a stack of laminations and just before the holding member leaves the top of the laminations, one of the separating members will be inserted between the laminations in the group thereby separating one or a number of laminations, depending upon the distance W between the plane of rotation of the bottom of the holding member and the plane of rotation of the edge of the separating member. The separated laminations will ride over the top of the separating member while the bottom of the separating member will hold the remaining laminations in the stack. As the separating member rides past the stack of laminations, the holding member will be rotated over the laminations and the laminations will be allowed to move up against the bottom of the holding member. Then, of course, as the next separating member contacts the stack of laminations the holding member moves out to allow the separating member to separate another lamination, or number of laminations. The operation of the separating mechanism 10' is shown clearly in FIGS. 7, 8 and 9 of the drawings. Of course, it will be understood that the separating mechanism 10 operates in substantially the identical fashion as the separating mechanism 10', therefore, it is believed only necessary to show one operation since it is believed that the manner of the continuous operation of the separating mechanism, either 10 or 10', will be readily understood by those skilled in the art.

Considering now FIGS. 7, 8 and 9, and particularly FIG. 7, there is shown a top and side view of the separating mechanism 10' in the beginning of the separating action. As shown particularly in the side view, a stack of laminations 70, 72 and 74 are being held in the stack by the bottom of the holding member 50 of the separating mechanism 10'. As can be seen from the top view in FIG. 7, the separating member 52 is out of contact with the stack of laminations, the separating member 54 is also out of contact with the laminations and the holding member 48 is on the opposite side, also out of contact with the stack of laminations. The direction of rotation of the separating member 10' is clockwise, as indicated by the arrow. During the rotation of the mechanism 10' as shown particularly in FIG. 8, the holding member 50 rides over the top of the stack of laminations 70, 72 and 74 and as it reaches the outer portion of upper lamination 70 the separating member 52 just begins to enter the stack of laminations between laminations 70 and 72. For purposes of this description, it is assumed that the distance W' is approximately equal to the thickness of a single lamination. Considering the thickness of laminations 70, 72 and 74 as being 12 mils then, of course, the distance W' will be approximately 13 mils. As can be seen in the side view of FIG. 8, the knife edge of the separating member 52 is just entering the laminations between laminations 70 and 72 and has begun to tilt lamination 70 away from the stack 72, 74. At the same time, the holding member 50 is rotating away from the stack of laminations and is just ready to release the upper lamination 70 for separation.

Considering now FIG. 9 of the drawings, it can be seen considering first the top view that the holding member 50 has now completely released the lamination stack and has moved away from such stack. The member 52

has now entered completely into the stack of laminations, the lower portion of the separating member 52 holding the laminations 72, 74 in the stack, and the upper side of the separating member 52 is separating the upper lamination 70 from the stack and is removing it therefrom.

Of course, it will be understood that as the separating member 10' continues to rotate it will move from the position shown in FIG. 9 to the position shown in FIG. 7. In moving to such position the holding member 48 will pass over the stack of laminations 72, 74 and will thereby hold the laminations stacked together as the knife or separating member 52 is removed from the stack of lamination. Of course, as it continues its rotation then the separating member 54 will enter the lamination stack between laminations 72, 74 thereby removing lamination 72 from the stack. Obviously, this operation will continue until all the laminations in the stack have been separated from the stack.

From the above description of both the construction of the separating mechanism 10 and 10' and the description of the operation thereof, it is believed clear that there has been shown and described a novel separating mechanism which may be utilized for automatically separating laminations from a group of laminations. While the present preferred embodiments of the invention have been described it will be understood by those skilled in the art that various changes and modifications may be made in such embodiments without departing from the invention herein disclosed, and the claims appended hereto are not limited to such embodiments but are intended to cover all such modifications as fall within the spirit and scope of such claims.

What is claimed as new and which it is desired to secure by Letters Patent of the United States is:

1. A separating mechanism for separating laminations comprising a rotatable member, holding means and separating means formed on said rotatable member, said holding means having a bottom portion rotating in one plane and said separating means having an edge portion rotating in a separate plane, said separate plane being

spaced from said one plane by a distance approximately equal to the thickness of the laminations to be separated, said holding means and said separating means being spaced about said rotatable member to enable said separating means to separate said laminations as said holding means releases said laminations.

2. A separating mechanism for separating laminations from a stack of laminations comprising a rotatable member, holding means and separating means formed about

10 said rotatable member, said holding means having a bottom portion rotating in a first plane and said separating means having an edge portion rotating in a second plane, the distance between said first plane and said second plane being substantially equal to the thickness of the laminations to be separated, said holding means and said separating means being spaced about said rotatable member such

15 that two separations occur during each rotation of said rotatable means.

3. A separating mechanism for separating laminations

20 from a stack of laminations comprising a rotatable member, said rotatable member being formed of two parts, one part of said rotatable member comprising a hub portion and a pair of separating members, the second part of said rotatable members comprising a pair of holding members, said holding members being removably

25 mounted to said first part of said rotatable member, said holding members having bottom portions and said separating members having edge portions, said bottom portions of said holding members rotating in a plane spaced from the plane of rotation of said edge portions of said separating members, the distance between said planes being substantially equal to the thickness of laminations to be separated.

4. A separating mechanism as claimed in claim 3 in

30 which said second part is angularly adjustable relative to said first part.
